UNITED STATES PATENT OFFICE.

JOHN R. GAMMETER, OF AKRON, OHIO, ASSIGNOR TO THE B. F. GOODRICH COMPANY, OF NEW YORK, N. Y., A CORPORATION OF NEW YORK.

HOT PLATE FOR VULCANIZING PRESSES.

Application filed April 23, 1923. Serial No. 634,027.

To all whom it may concern:

Be it known that I, JOHN R. GAMMETER, a citizen of the United States, residing at Akron, in the county of Summit and State 5 of Ohio, have invented a certain new and useful Hot Plate for Vulcanizing Presses, of which the following is a specification.

This invention relates to the construction of the hot-plate 17 shown in my Patent 10 1,414,507 of May 2, 1922, embodying a duct formed and arranged in a novel manner in the plate for the passage of the steam or other heating fluid.

These plates are commonly made of steel 15 and the usual method of forming the duct heretofore has been to drill the plate from one edge in the plane thereof with a number of parallel holes, then drill two holes at right angles to the first series of holes near 20 opposite edges of the plate to form connecting passages, then drive in plugs at intervals in staggered fashion into these two connecting holes so as to make a single continuous passage, and finally plug up the ends of all 25 the intermediate holes at the edges of the plate, leaving only two terminal openings for connecting the pipes for the intake and discharge of the heating fluid.

This mode of construction, besides being 30 comparatively expensive, has the disadvantage that it is practically impossible to clean scale and sediment from the open portions of the transverse connecting holes owing to the presence of the plugs in the adjacent 35 closed portions and these plugs, unless very accurately fitted, may tend to become dislodged.

It is the object of my present invention to overcome these objections.

40 Of the accompanying drawings, Fig. 1 is a side elevation showing a two-mold vulcanizing press provided with hot-plates constructed according to my invention.

Fig. 2 is a horizontal section on the line 45 2—2 of Fig. 1.

In the drawings, 10 is the base of the press provided with a hydraulic cylinder 11, having a plunger 12 which carries the movable press-platen 13 at its upper end. 14 is 50 the upper fixed press-platen or cross-head and 15, 15 are the vertical tie-rods connecting the base with the upper platen 14.

16, 16 are a series, in this instance three, of hot-plates, of which the bottom and top 55 ones may be attached to the movable and

fixed press-plantens 13 and 14 respectively, while the middle plate is formed with forked guide-lugs 17 running on a series of fixed, vertical guide-rods 18.

The construction of one of the hot-plates 60 16 is illustrated in detail in Fig. 2. From one or both of the front and rear edges of said plate I drill clear through the plate a series of diagonal holes or duct courses 65 19 which meet or run into each other in staggered fashion at apexes in two series of common holes 20 on the respective front and rear edges, and I then tap out all of the apex holes and insert screw-threaded 70 plugs 21 therein, the result being a continuous zig-zag fluid passage. The two holes at the beginning and end of this passage are likewise tapped for the reception of the screw-threaded ends of the intake and discharge pipes 22, 23 respectively.

Where more than one of these hot-plates 75 16 is provided, they are preferably connected in series, as here shown, from top to bottom, with the discharge end of one duct connected through a telescopic pipe 24 with the intake end of the next duct, there being a final discharge through the pipe 25. Between the hot-plates are shown two vulcanizing molds 26.

By constructing the hot-plates in this 80 fashion I not only reduce the cost of manufacture and attain a simplified construction but also provide a series of straight passages which, upon removal of the plugs 21, and the connections, allows the insertion of 85 a cleaning tool such as those employed with water-tube boilers for removing scale and sediment from these passages, thereby maintaining the efficiency of the hot-plate and also providing a structure which fully complies with all boiler inspection laws to which 90 apparatus of this type is often subject.

Variations in detail may, of course, be 95 made within the scope of my invention.

I claim:

1. A hot-plate having a zig-zag fluid passage therein formed of straight courses aping in a series of apertures at the edge of said plate, each aperture common to a pair of such courses, and means for closing 105 said apertures.

2. A hot-plate having a zig-zag fluid passage therein formed of straight courses aping in two series of apertures at opposite edges of the plate, each aperture com- 110

mon to a pair of such courses, and removable screw plugs forming closures for said apertures.

3. A heating platen having cross-passages directly communicating with each other at their ends, and tubular connections carried by said platen and communicating with a plurality of such passages whereby a heating fluid may be circulated through the 10 passages of the platen.

4. A steam platen comprising a thin plate of relatively large dimensions substantially rectangular in shape having a series of cross-passages directly communicating with 15 each other and forming a continuous path;

and tubular connections carried by said platen and communicating with a plurality of such passages whereby a heating fluid may be circulated through the passages forming the continuous path of the platen. 20

5. A steam platen comprising a thin plate having cross-passages following straight lines; such passages extending entirely through the platen, and removable plugs closing the ends of said passages; pairs of 25 the latter communicating with single outlets closed by said plugs.

In witness whereof I have hereunto set my hand this 9th day of April, 1923.

JOHN R. GAMMETER.
